W. N. PEAK.

WALL PAPER.

No. 16,961.

Patented Oct. 26, 1886.

UNITED STATES PATENT OFFICE.

WILLIAM N. PEAK, OF BROOKLYN, NEW YORK.

DESIGN FOR WALL-PAPER.

SPECIFICATION forming part of Design No. 16,961, dated October 26, 1886.

Application filed August 20, 1886. Serial No. 211,455. Term of patent 3½ years.

To all whom it may concern:

Be it known that I, WILLIAM N. PEAK, of the city of Brooklyn, in the county of Kings and State of New York, have invented and produced a new and original Design for Wall-Paper, of which the following is a specification.

The nature of my design is fully represented in the accompanying photograph, to which reference is made.

The design consists, principally, of a vase-shaped figure, A, connected to a foliated base, B B. Leading from the central point of the figures B B is a diamond-shaped figure, C, which is nearly surrounded by the members d d of a spider-shaped figure, D. Above the vase-shaped figure A is another spider-shaped figure, E, and surmounting this is a short curved band, F, consisting of the concentric arcs a a, between which appears a complex curved border or band, a', as shown in the accompanying photograph. At either side of

the vase-like figure A appears a scalloped figure, G, as shown in the accompanying photograph.

I claim—

1. The design for wall-paper herein shown and described, the same consisting of a vase-like figure with a foliated base and a diamond-shaped figure below the base.

2. The design for wall-paper herein shown and described, the same consisting of a vase-like figure, A, a diamond-shaped figure, C, and two spider-shaped figures, E D, above and below the vase-like figure, respectively.

3. The design for wall-paper herein shown and described, the same consisting of a vase-like figure, two spider-shaped figures, a foliated base for the vase figure, and a crown or curved band above the vase.

WILLIAM N. PEAK.
